UNITED STATES PATENT OFFICE.

WENDELL P. PUTNAM, OF WATERTOWN, MASSACHUSETTS.

CURTAIN-FIXTURE.

SPECIFICATION forming part of Letters Patent No. 279,802, dated June 19, 1883.

Application filed May 4, 1883. (No model.)

To all whom it may concern:

Be it known that I, WENDELL P. PUTNAM, a citizen of the United States, residing at Watertown, in the county of Middlesex and State 5 of Massachusetts, have invented certain new and useful Improvements in Curtain-Fixtures; and I declare that the same are fully described in the following specification and illustrated in the accompanying drawings.

10 This invention is designed to lock together the roller and spindle of a balance curtain-fix-
ture so that the spring which actuates them shall not lose its tension and become uncoiled when the spindle is removed from the brack-
ets. Such a lock is operative until the roller 15 is replaced in the brackets, when a slight down-
ward movement of the shade causes a disen-
gagement of the parts and leaves the roller free
to rotate either way around the stationary
20 spindle, the locking device lying dormant.

This invention consists in a cam-shaped col-
lar fixed radially on the spindle and a sliding
double hook or bar hung thereon in such po-
sition as to embrace the spindle and permit
25 free rotation of the roller around it when
mounted for use, but to become wedged be-
tween the cam of the collar and the interior
wall of the tubular roller or its cap when the
spindle is dismounted.

30 The peculiarities of this invention will be
clear from the drawings, in which Figure 1 is
a longitudinal section of the roller; Fig. 2, de-
tached views of the locking parts; Fig. 3, a
top view of the same. Fig. 4 is a transverse
35 section, showing the dormant position of the
lock while the roller is mounted for use; and
Fig. 5, a similar view of the parts locked to-
gether.

The roller A and its end cap, B, revolve about
40 the spindle C, increasing or decreasing the ten-
sion of the spring D, arranged as is usual in

balance-fixtures. A radial flange or collar is
formed on the spindle, within the roller end,
the upper edge of such collar forming a cam,
F, with a surface gradually approaching the 45
walls of the spring-chamber. A bent bar or
hook, H, is hung upon this cam-surface so as
to pass around beneath the spindle with space
sufficient to permit a movement of the hook
from its dormant position to that where it en-
gages with both the cam and the inner wall of
the roller or cap and locks the spindle and
roller together. This movement occurs when
the spindle flies on being released from the
bracket which had prevented its rotation, and 50
it arises from the inertia of the hook at the
instant the spindle starts to rotate, the rotary
impulse of the spindle and cam serving to lift
the hook into engagement with the cam and
roller, as shown in Fig. 5. The ends of the 55
hook extend down far enough below the cam-
surface so as not to disengage from it while
within the spring-chamber. A projection, G',
formed adjacent to the cam keeps the hook
from sliding down into contact with the roller 60
in its mounted position, as shown in Fig. 4.
Another projection, G, might serve the same
purpose.

I claim as my invention—

As a locking device for spring curtain-roll- 70
ers the spindle C and cam F, with projection
G, in combination with a sliding hook mounted
thereon embracing the spindle and adapted to
engage with said cam and roller, substantially
as and for the purpose set forth.

In testimony whereof I hereto affix my signature in presence of two witnesses.

WENDELL P. PUTNAM.
